NONREFILLABLE BOTTLE

Alvin M. Whitney, Bradford, Pa., assignor to
Celloseal Company, Bradford, Pa., a corpora-
tion of Pennsylvania

Application May 17, 1935, Serial No. 22,073

1 Claim. (Cl. 215—8)

The present invention relates to new and useful improvements in non-refillable bottles and has for its primary object to provide, in a manner as hereinafter set forth, a bottle comprising a novel construction of closure through the medium of which it may be readily ascertained if the bottle has been opened, thus preventing refilling of said bottle without detection.

Another very important object of the invention is to provide a non-refillable bottle of the aforementioned character which includes novel means for preventing tampering with the closure thereof.

Other objects of the invention are to provide a non-refillable bottle which will be comparatively simple in construction, strong, durable, reliable in use, compact, and which may be manufactured at low cost.

All of the foregoing and still further objects and advantages of the invention will become apparent from a study of the following specification, taken in connection with the accompanying drawing wherein like characters of reference designate corresponding parts throughout the several views, and wherein:—

Figure 1 is a view in vertical section through the invention.

Figure 2 is a vertical sectional view, showing the bottle after it has been opened.

Figure 3 is a detail view in vertical section through the bushing.

Figure 4 is a detail view in side elevation of the indicator.

Figure 5 is a detail view in vertical section through the frangible indicator retaining bag.

Figure 6 is a perspective view of an instrument which may be used for opening the bottle.

Referring now to the drawing in detail, it will be seen that the embodiment of the invention which has been illustrated comprises a neck 1 which rises from the bottle 2, said neck including a restricted lower portion 3. The neck 1 is internally tapered and mounted in the upper portion of said neck is a bushing 4 of suitable material, preferably glass, said bushing being cemented in position, as at 5. At its upper end, the bushing 4 terminates in an external flange 6 which extends over the upper end of the neck 1.

In its lower portion, the bushing 4 has formed therein a circumferential groove 7 in which an explosive 8 is placed prior to the insertion of said bushing in the neck 1. The groove 7 is also for the reception of the internal bead 9 on the upper end of a frangible bag 10 which depends from said bushing 4 in the neck 1. It will be observed

that the upper portion of the frangible bag 10 extends between the bushing 4 and the neck 1 of the bottle. The lower end portion of the bore 11 of the bushing 4 receives an indicator plug 12 which the bag 10 encloses. The indicator plug 12 terminates, at its lower end, in a point 13 which facilitates pushing said indicator plug through the frangible bag 10.

The upper end portion of the bottle neck 1 is externally threaded to receive a removable cap 14. The cap 14 is provided with a gasket 15 of suitable material, such as cork, which is engageable on the upper end of the bushing 4. The reference numeral 16 (see Figure 6) designates an instrument to be used in opening the bottle. 15

In use, after the bottle 2 has been legitimately filled, the bushing 4, with the explosive 8 in the groove 7, and the retaining bag 10 and indicator plug 12 mounted thereon, is inserted in the neck 1 and cemented. The screw cap 14 is then applied. When it is desired to remove the contents of the bottle, the cap 14 is removed and the indicator plug 12 is pushed downwardly through the frangible retaining bag 10 (see Figure 2) by inserting the instrument 16, or any other suitable instrument, in the bore 11 of the bushing 4. The restricted portion 3 of the neck 1 prevents the indicator plug 12 from dropping into the bottle 2. 20 25

It will thus be seen that with the bag 10 ruptured and the plug 12 dislodged from the bushing 4 it will be readily apparent to any one examining the bottle that said bottle has been opened. The construction of the plug 12 is such that removal of said plug through the bore 11 of the bushing 4 will be impossible. It will also be noted that it 30 will be impossible to remount the plug 12 in the bushing 4 or renew the frangible bag 10 without removing said bushing 4 from the neck 1. Should the bottle be subjected to heat in an attempt to remove the bushing 4 said bottle will be destroyed 40 by the explosive 8. It may be well to here state that the frangible bag 10, in addition to being waterproof, is preferably of acid or chemical resisting material. 45

It is believed that the many advantages of a non-refillable bottle constructed in accordance with the present invention will be readily understood, and although a preferred embodiment of the invention is as illustrated and described, it is to be understood that changes in the details of construction and in the combination and arrangement of parts may be resorted to which will fall within the scope of the invention as claimed. 50

What is claimed is:—

A non-refillable bottle comprising a neck in- 55

cluding a restricted portion, a bushing fixed in said neck, said bushing having an annular groove therein, a plug removably mounted in the lower portion of the bushing and depending therefrom, a frangible retaining bag mounted on the lower portion of the bushing and depending therefrom and enclosing the plug, said bag including an internal bead in its top portion engaged in the

groove, the plug including a pointed lower end adapted to penetrate the bag, and a removable cap threadedly mounted on the neck, the restricted portion of said neck constituting means for arresting the plug when said plug is dislodged 5 from the bushing.

ALVIN M. WHITNEY.
